Inventor

Attorney.

UNITED STATES PATENT OFFICE.

CHARLES EDWARD CORADO, OF WINNIPEG, MANITOBA, CANADA.

HYDROCARBON BURNER.

1,413,968.

Specification of Letters Patent. Patented Apr. 25, 1922.

Original application filed April 15, 1920, Serial No. 374,225. Divided and this application filed August 12, 1921. Serial No. 491,846.

To all whom it may concern:

Be it known that I, CHARLES E. CORADO, a subject of the King of Great Britain, and resident of the city of Winnipeg, Province 5 of Manitoba, Dominion of Canada, have invented certain new and useful Improvements in Hydrocarbon Burners, (for which I have filed application in Dominion of Canada April 15, 1920, Serial No. 240,101;) 10 and I do hereby declare that the following is a full, clear, and exact description thereof.

My invention relates particularly to burners of the type disclosed in my pending application Serial No. 374,225 of which this 15 is a divisional part, and has for its object to provide a burner having a detachable chimney supporting attachment which may be removed when a chimney is not used. A further object is to provide a burner in 20 which a more complete combustion will be obtained by providing the cap with a plurality of air inlet openings arranged to produce a uniform distribution of air to the zone of combustion.

25 To this end the invention consists of the combination, construction and particular arrangement of the parts hereinafter described and pointed out in the claims.

For full comprehension, however, of my 30 invention reference must be had to the accompanying drawings in which similar reference characters indicate the same parts, and wherein:

Figure 1 is a side elevation of my improved attachment in use;

Figure 2 is a plan view thereof; and

Figure 3 is a detail perspective view of the attachment alone.

In the construction illustrated in the drawings which is the preferred embodiment of my invention, the base is indicated at 2 and the cap at 2^a. The lower edge of the latter terminates in a circumferential bead 3 and its dome is provided with the usual 45 flame opening 4 and a plurality of air inlet openings. The latter are of semi-circular form and are located one on each side of the flame opening adjacent the top of the cap as indicated at 5 and 6 respectively, and two 50 on each side of a plane perpendicular to the length of the flame opening and adjacent the bead 3 as indicated at 7, 8, 9 and 10 respectively.

The chimney supporting attachment is 55 constructed and arranged to be detachably

mounted upon the burner and consists of a flat ring 12 having depending arms 13, 14 and 15 which are adapted to be sprung over the bead 3 on the burner cap with the ring 60 encircling the dome of the latter.

The extreme lower ends of the arms 13 and 14 are bent outwardly as at 16 to present inclined surfaces 17 which enable the attachment to be sprung into position by a slight downward pressure, each arm adjacent the bent-out portion being offset to provide a seat 18 from which the bead 3 will not become displaced in service. The arm 15 is of a different construction to that of the arms 13 and 14 in that it is bent inwardly and upwardly as at 19 in U form, the portion 19 having an offset 20 to receive the bead on the cap and being extended upwardly through an opening 21 in a radial extension 22. The portion of this extension 75 which is located above the ring constitutes a spring jaw 23 which cooperates with two fixed jaws 24 and 25 in gripping the usual bead 26 on the lower end of the lamp chimney. The upper end of the spring jaw is 80 bent upwardly and outwardly to present an inclined surface 27 which is adapted to facilitate the positioning of the chimney. All of the jaws have concave gripping faces 28 to receive the bead on the chimney. 85

What I claim is as follows:

1. In a hydrocarbon burner the combination with the body thereof including a base portion and a cap mounted thereon said cap having a circumferential bead on its lower 90 edge; of chimney supporting means independent of said cap and detachably mounted thereon said means consisting of a ring constructed and arranged to encircle the upper end of the cap and having a plurality of fixed chimney retaining members upon its top; a resilient retaining member adapted to coact with said fixed members, and resilient means secured to the said ring and adapted to be sprung over the bead on said cap. 95

2. In a hydrocarbon burner the combination with the body thereof including a base portion and a cap mounted thereon said cap having a circumferential bead on its lower edge; of chimney supporting means independent of said cap and adapted to be detachably mounted thereon, said means consisting of a ring constructed and arranged to encircle the dome of the cap and presenting a flat chimney supporting surface, said 105 110

ring having a plurality of downwardly projecting resilient arms adapted to be sprung over the bead on said cap the free end of one of said arms being extended upwardly 5 above the ring and terminating in a spring jaw, and fixed jaws upon the top of said ring adapted to cooperate with said spring jaw in gripping a chimney.

3. A chimney supporting attachment for 10 hydrocarbon burners consisting of a ring having spaced fixed jaws upon the top thereof and having a radial extension diametrically opposite said jaws, such extension having an opening therein, and means for 15 detachably securing the attachment upon a

burner, said means consisting of downwardly projecting resilient arms secured to the underside of said ring, one of said arms being turned upwardly in substantially U-form and extended through said opening in 20 the form of a jaw adapted to coact with the said fixed jaws in gripping a chimney.

In testimony whereof I have signed my name to this specification in the presence of two witnesses.

CHARLES EDWARD CORADO.
